UNITED STATES PATENT OFFICE

2,387,391

STEAM BOILER

George H. Green, Oakland, Calif.

Application June 10, 1944, Serial No. 539,712

1 Claim. (Cl. 122—41)

This invention relates to steam boilers.

It is the principal object of the present invention to provide an improved and simplified steam boiler of the flash boiler type which is highly efficient and which may be built relatively small in size so that it may be employed in the automotive and aircraft fields in connection with comparatively small steam engines.

One form which my invention may assume is exemplified in the following description and illustrated by way of example in the following drawing, in which:

The figure is a view in central vertical section through a boiler embodying the preferred form of my invention.

Referring more particularly to the accompanying drawing, I have there illustrated a steam generating boiler 10 of the flash boiler type. This boiler is intended for use in connection with steam automotive and aircraft engines and consequently is capable of being built relatively small in size with rapid generating characteristics.

The boiler comprises a spherical dome 11 enclosed within a heat insulating casing 12. The latter is formed with an interior semi-spherical chamber 14, within which the upper half of the dome 11 nests with a slight spacing therebetween as shown.

The casing 12 is fitted with a stack 15 centrally located at its upper end communicating with the chamber 14 so that the products of combustion seeking to pass from the lower end of the casing will travel through the narrow spacing between the dome 11 and the casing 12 to the stack. This will effect a passage of the heated gases over the exterior surface of the entire upper half of the dome and effect an exchange of heat therebetween.

In its upper end the dome 11 is fitted with a steam outlet fitting 16 having a connection 17 for conducting steam to the point of use. The fitting 16 is also fitted with a safety valve 18 for obvious reasons.

The lower end of the casing 12 includes a combustion pot 19 which is fitted with fuel burners 20 and air controls 21. Obviously, any suitable means may be provided for generating heat within the casing 12 and that shown is by way of example only.

For generating steam, I provide a plurality of steam generating coils 22 which are arranged exteriorly over the lower half of the dome 11. The coils 22 are formed to conform to the shape of the dome so that the latter nests therein at a spaced distance therefrom as shown. Each coil

comprises three turns of tubing connected at one end to a feed water manifold 23 and at the other end to a steam manifold 24. The feed water manifold is connected to a feed water pipe 25 extending centrally and upwardly into the casing 12 as illustrated.

The steam manifold 24 is connected with a nozzle 26 extending into the dome 11. The nozzle 26 is fitted with a check valve 27 to permit steam

10 to enter the dome but not discharge therefrom.

In operation of the boiler it is constructed and assembled substantially as illustrated and described and the feed water pipe 25 is connected with a feed water tank. As in standard practice,

15 a feed water pump will naturally be associated with the feed water pipe 25 to feed water thereto at the proper rate. The connection 17 is connected with the engine or other medium employing the steam generated in the boiler. It 20 should be pointed out here that the present boiler is a comparatively small boiler and its principal use is in the aircraft and automotive field. For this purpose the casing 12 may be provided with suitable means for mounting the boiler in an 25 automotive frame or otherwise. In that this mounting does not form a part of the invention, it is not illustrated.

To commence the boiler in operation, combustion

30 is effected in the combustion pot 19 by ignition of the fuel injected by the burners 20. These burners may be upwardly directed in a sort of tangential fashion somewhat as illustrated so as to obtain the maximum efficiency from the heat generated.

As the steam is generated in the coils 22, the steam will pass into the steam manifold 24 and be injected into the dome 11. The steam may be withdrawn from the dome from the take off fitting 16 through the connection 17. If the

35 steam pressure within the dome becomes excessive, the automatic safety valve 18 will naturally open until the pressure is reduced to a predetermined pressure.

The heated gases generated within the lower 40 end of the casing 12 will be caused by the formation of that casing to pass upwardly around the coils 22 to effect an exchange of heat therewith. Thereafter these gases will pass through the thin semi-spherical chamber 14 in close contact with

45 the upper half of the dome 11 and effect an exchange of heat therewith. From the chamber 14 the gases will discharge through the stack 15. By the construction and formation of the dome, the generating coils 22 and the casing 12 a maximum exchange of heat will be effected so that

the boiler will be very efficient and will generate steam of high temperature very rapidly.

From the foregoing it is obvious that I have provided a very simple and efficient boiler of a type capable of use in connection with small steam engines for automotive and aircraft use.

While I have shown the preferred form of my invention, it is to be understood that various changes may be made therein by those skilled in the art without departing from the spirit of the invention as defined in the appended claims.

Having thus described my invention, what I claim and desire to secure by Letters Patent is:

A steam boiler of the character described comprising a spherical dome, a plurality of separate generating coils surrounding the lower portion

of the dome, said coils being wound about the vertical axis of the dome and surrounding the lower half of the dome, said coils conforming to the contour of the dome and lying in close proximity thereto, a feed water manifold to which one end of each coil is connected, steam manifold to which the other end of each coil is connected, said steam manifold being in communication with the interior of the dome, a casing enclosing the dome and coils, means for generating heat within the casing beneath the dome, said casing being so formed interiorly that the products of combustion will pass over the entire exterior area of the dome.

GEORGE H. GREEN.
